UNITED STATES PATENT OFFICE.

EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

FILLING CLAMPING AND PARTING MECHANISM FOR SHIFTING SHUTTLE-BOX LOOMS.

Application filed October 29, 1925. Serial No. 65,584.

In the weaving of cloth with a shifting shuttle box loom or a loom employing a plurality of filling carriers, each of which is independently active in the weaving operation, a loop of filling will be left extending along the selvage from the point where any given filling carrier or shuttle went out of action to the point where it was restored to action. The length of these loops will obviously depend upon the width of the stripes or cross bars woven. When the stripes or cross bars woven by a given filling carrier are widely separated, the loops of filling between these stripes will be long. When more than two filling carriers are employed, these loops may overlap, may be of various lengths, and several may extend along portions of the selvage at the same time. When such loops are formed, they must be removed from the selvage to make the fabric salable and it is difficult, if not impossible, to remove them by the usual singeing operations and it is laborious and expensive to remove them by hand. In a prior Patent, No. 514,603, November 11, 1924, I provided means acting automatically during the weaving operation by which such loops were first severed and then the ends cut off close to the selvage.

The object of the present invention is to provide means which prevents the formation of such loops along the selvage. In other words, the present invention, instead of permitting the formation of the undesirable loops and then removing them, prevents their formation in the first instance.

The object of the invention is further to provide filling clamping and parting mechanism located adjacent the selvage on the drop box side of a shifting shuttle box loom and to cause this mechanism, after a shuttle is shifted from active to inactive position, to seize or clamp the filling extending from the selvage to the inactive shuttle and to part this filling between the selvage and the point at which it is seized or clamped.

The object of the invention is further to provide a mechanism for this purpose in a shifting shuttle box loom having any number of boxes and which will operate upon any shift of these boxes in either direction.

These and other objects and features of the invention will appear more fully from

the accompanying description and drawings and will be particularly pointed out in the claims.

Since the present invention relates entirely to the prevention of the formation of loops along the selvage which would otherwise result in the weaving operation upon the shifting of the boxes in a shifting shuttle box loom, and since the construction and operation of shifting shuttle box looms are well known and familiar to those skilled in the art, and since the invention is applicable to a wide range of loom constructions with the application of ordinary mechanical skill, it is necessary here to illustrate and describe only those features of an ordinary type of shifting shuttle box loom sufficient to disclose in connection therewith a simple and preferred form of construction embodying the present invention.

In the drawings:

Fig. 1 is a side elevation of a portion of a shifting shuttle box loom of a well-known 4 X 1 type with a preferred form of the present invention adapted to such a type embodied therein.

Fig. 2 is a top plan view of a portion of the loom shown in Fig. 1 and on a larger scale.

Fig. 3 is a view in side elevation and partially in vertical cross section taken on the line 3—3 of Fig. 2.

Fig. 4 is a view similar to Fig. 3 with the mechanism in a different position.

Fig. 5 is a front elevation of the main portion of the construction shown in Fig. 2.

Fig. 6 is a detail in side elevation of one of the clamping blades.

The side frame 1 at the drop box side of the loom is shown with the breast beam 2 extending laterally therefrom and with the main elements of the box shifting mechanism mounted on the frame. The lay 3 is operated to swing forward and backward or toward and away from the breast beam in the usual manner and carries, in the case illustrated, the four shuttle boxes 4, 5, 6 and 7 with their corresponding shuttles 8, 9, 10 and 11, each provided with a suitable filling carrier. The shuttle boxes are suitably guided for vertical bodily movement on the lay and are supported on the lifting rod 12, which is guided near its lower end in a guide

13 carried by an arm 14 extended from the usual lay rocker shaft so that the lifter rod swings backward and forward with the lay. At its lower end the lifter rod carries a stud 5 15 to which is pivoted an arm 16 having pivotally connected to its upper end at 17 another arm 18. The arms 16 and 18 are held together by a spring 19. At the point where the arms 16 and 18 contact, each is 10 provided with half of a bearing for a stud 20 at the end of the lever 21 of the usual box motion. The details of such a box motion it is unnecessary to illustrate and describe, but there is herein shown the usual star gear 15 22 having a movement of rotation on the shaft 23 every two picks, the front shaft 24, the back shaft 25, the gears 26 and 27 provided with blank teeth and carried by the front and back shafts respectively and the 20 eccentric connections between these gears and the lever 21. As is well-known, the gears 26 and 27 are shifted into and out of cooperation with the star gear 22 by suitable automatic or pattern mechanism, so that the lever 21 is rocked to shift the rod 12 and bring any one of the boxes into position to render its shuttle active in the weaving operation, thus rendering the previously active shuttle inactive. The only detail in 30 the construction and operation of this box motion of consequence in connection with the disclosure of the present invention is the arm 16. This arm is conveniently utilized as an actuating element of the mechanism illustrated because it is conveniently located and moves with the boxes so that its movement is exactly proportionate to the movement of the boxes in shifting from one position to another.

35 40 In the construction illustrated, the clamping and parting elements for the filling are separate instrumentalities separately operated, but this is simply for convenience and any suitable arrangement may be employed 45 within the scope of the invention.

50 The filling parting elements are shown as an ordinary type of device such as is embodied in a thread cutting temple. Such a temple 28 is shown provided with the usual shank 29 sliding in the stand 30 adjustably secured to the breast beam by the screws 31. The temple is yieldingly projected rearwardly by a spring, not shown, in the stand 30 in accordance with the usual practice, and a 55 heel 32 projecting downwardly from the temple, when struck by the lay, causes the temple to move forwardly to an extent determined by the character of the material woven.

60 65 The parting mechanism, which is shown as of the type disclosed in the patent to Stimpson No. 1,366,084, January 18, 1921, is mounted in the temple closely adjacent the path of the selvage 33 and comprises a fixed cutter blade at the rear face of the temple and a

hook-shaped blade 34 forming part of a movable cutter member rocking vertically and sliding longitudinally in a slot in the temple. This cutter member is provided with a depending heel 35. A spring 36, engaging at its lower end a stud 37 on the heel 35 and at its upper end a stud 38 on the temple, acts to maintain the movable cutter member in its rearward open projected position, as shown in Figs. 3 and 4. When the lay beats up it strikes the heel 35, rocking the movable cutter member downwardly and carrying it forwardly so that any filling extending in its field of action is caught between the hooked blade 34 and the fixed 75 blade and severed close to the selvage, all in a well known and familiar manner.

The mechanism for seizing, retaining or clamping the filling extending to a filling carrier or shuttle which has been shifted to inactive position is also positioned adjacent the selvage and close to the parting mechanism. In the particular form of the invention herein illustrated, this clamping mechanism is normally located out of position to receive the filling or in a position well forward of the fell and with the clamping members closed. Upon the shifting of the shuttle boxes the clamping mechanism is automatically moved into a position to receive the filling or into a position slightly in advance of the fell with the clamping members open. Upon the conclusion of the beat-up after the shifting of the boxes, this clamping mechanism is closed to clamp the filling extending to the shuttle shifted to inactive position and is then moved bodily forward to its normal position. In the construction illustrated, the clamping mechanism is conveniently mounted in a two-part support comprising the plates 39 and 40. This support is rigidly mounted, in this case, by means of a bracket 41 extending from the upper plate 39 and adjustably secured by the screws 42 to the temple stand 30. The plates 39 and 40 are secured together by the screws 43 and are formed to present a central, longitudinal guideway. In this guideway is mounted the slide bar 44 which is cylindrical at its forward end and preferably rectangular at its rear section 45. A helical spring 46 located in the channel of the support abuts against a shoulder at the forward end of the support and against the end of the rectangular section 45 at the rear so that this spring acts normally to project the slide bar rearwardly. The slide bar is held in its forward position by a latch shown as a lever 47 fulcrumed at 48 in the bifurcated portion of the slide bar 45. The forward arm 49 of this lever is provided with a downwardly projected stud 50 adapted to fit in a hole 51 in the top plate 39 of the support. A spring 52 connected to the arm 49 passes down through a hole 130

in the section 45 of the slide bar and connects to a finger 53 extending from an arm 54 rigid with the slide bar. This spring acts to hold the latch in locking position 5 with the stud 50 in engagement with the hole 51 when the slide bar is retracted or in its normal position.

The arm 54 extends downwardly from the slide bar and then rearwardly alongside 10 and adjacent the selvage and close to the temple. This arm at its rearward end is flared and provided with a central notch or recess into which the filling is guided by the flared end. The clamping mechanism 15 proper is conveniently secured to this arm 54 and comprises two fixed blades 55 and 56 with an interposed movable blade 57, operating after the manner of shears. The fixed blades 55 and 56 are the same in construction and are preferably made of some tough but relatively soft material such as fibre board. A portion of one of these blades is illustrated in Fig. 6 and it will be noted that the forward end is provided at 20 the top edge with fine notches sloping downwardly and rearwardly. These notches assist in retaining the filling. If desired, one or more of the clamping blades may be faced or covered with felt or other suitable 25 adherent material for this purpose. The movable blade 57 is preferably of metal such as steel. The blades are mounted upon a screw stud 59 extending into the arm 54 with a spring 60 seated beneath the head 30 of the stud 59 and acting to press the blades together and against the arm 54. A second stud 61 connects the forward end of the fixed blades 55 and 56 and extends through a large hole in the movable blade 57 and is 35 also secured in the arm 54. The movable blade extends forwardly and is provided with a depending heel 62 and an upwardly extending arm 63 provided with a projection 64 extending laterally over the rearward arm 65 of the latch lever 47. The pressure exerted by the spring 60 is such 40 that the clamping mechanism is firmly held frictionally either in open or closed position.

50 The operation of the clamping mechanism will now be apparent. Normally the parts stand as shown in Figs. 2 and 3 with the slide bar in its forward position and locked in this position by the latch arm 49, 55 thus holding the clamping mechanism in its forward position or out of position to receive filling. In this position the clamping members are closed so as to hold clamped any filling which has previously 60 been positioned in the clamping mechanism. The arm 63 stands substantially vertically in this position with the projection 64 above and free from the arm 65 of the latch lever. In order to bring the clamping mechanism 65 into position to receive filling, it is only

necessary to depress the arm 63. When thus depressed, this arm acts as a latch release because the projection 64 coming into contact with the arm 65 of the latch rocks the latch about its fulcrum, withdrawing 70 the stud 50 from the hole 51 and thus allowing the entire clamping mechanism to be projected rearwardly or into the position shown in Fig. 4. But the depression of the latch release 63 rocks the movable blade 75 to which it is rigidly connected into open position. Hence the depression of the latch release 63 effects both the opening of the clamping mechanism and its bodily projection rearwardly to operative position. 80

In the present construction the operation of the latch release is effected upon a shifting of the shuttle boxes so that whenever there is a shift of the shuttle boxes in either direction to shift an active shuttle to inactive position and bring an inactive shuttle into active position, the clamping mechanism is opened and projected rearwardly. In the construction illustrated, since the shift of the boxes takes place before the 85 conclusion of the beat-up of the lay, the clamping mechanism is thus projected rearwardly and in open position to receive the filling extending from the selvage to the shuttle which has just been shifted to inactive position. Consequently as the lay concludes its beat-up and this filling is beaten in, the clamping mechanism is closed and moved to its forward position by the lay thus seizing and clamping adjacent the 90 selvage the filling extending to the inactive shuttle. The clamping mechanism is conveniently pushed forward by a bunter 66 on the lay which strikes the heel 62, rocking the movable clamping member into 95 closed position and then carrying the entire clamping mechanism forward until it is caught and locked by the latch arm 49.

The filling is crowded by the movable blade 57 down in between the fixed blades 100 55 and 56. The filling will usually stay in this position even if the clamping mechanism is opened because there is no strain on the filling sufficient to pull it out of its crimped position between the fixed blades. 105 The hold upon the filling is aided by the fact that the fixed blades are of fibre board or some similar soft material and preferably also by the serrations or slots 58 into which the filling is also crowded. Consequently, when there are a plurality of shuttles in inactive position, as, for example, three in the present case, the filling 110 will not be released from the clamping mechanism by the opening of the mechanism and its projection to rearward position.

When the clamping mechanism has returned to its forward position holding the filling extending to the shuttle just rendered 115

inactive, the filling extending from the clamping mechanism to the fell is then, or shortly afterward, brought within the field of action of the parting mechanism carried by the temple, already described, and is parted thereby.

The filling end thus held by the clamping mechanism is retained thereby until a shift of the shuttle boxes takes place to bring the shuttle carrying this filling again to active position. Before this shuttle starts on its first pick, the clamping mechanism has been closed and returned to its normal forward position so that the end of the filling is still held as this pick is laid.

Various forms of mechanism may be provided for operating the latch release whenever a shift of the shuttle boxes takes place and a simple and preferred construction for that purpose is illustrated. An actuator in the form of a rod 67 is mounted for vertical reciprocation in bearings 68 and 69 on the loom side 1. The arm 70 rigidly connected to the arm 16 of the box motion extends forward and has a semi-universal connection with the rod 67. This is secured by having the arm slide in a member 71 pivoted at 72 in a sleeve 73 adjustably secured by a set screw 74 on the rod 67. Thus it will be seen that the actuator or rod 67 is connected to the box shifting mechanism and actuated thereby to move proportionately with the shifting movement of the boxes.

The rod 67 has secured thereto and projecting laterally therefrom in parallelism a plurality of striker arms, one less in number than the boxes, and these striker arms are spaced apart a distance equal to one unit of movement of the rod. There being four boxes in the loom illustrated, there are three of these striker arms 75 secured to the rod by the set screw 76. At their free ends these striker arms move in a path intersecting a switch 77 pivotally mounted at 78 on the latch release 63. This switch, when a striker arm is moved downwardly against it, releases the latch 49, and when the striker arms move upwardly, this switch moves on its pivot to allow the passage of the striker arms. Consequently, whenever there is a downward shift of the boxes, these striker arms effect the release of the latch.

In order to provide for the release of the latch upon an upward shift of the boxes, further mechanism is necessary, and for that purpose a converter lever is shown fulcrumed at 79 on a standard 80 projecting upwardly from the breast beam. This converter lever has one arm 81 bent at its end 82 to extend above the latch 77 and is normally held in this position by a spring 83 extending from the other arm 84 of the lever to the standard 80 and holding the

arm 84 against a projection 85 on the standard. A second switch 86 is fulcrumed at 87 on the arm 84 of the converter lever and extends into the path of the branches 88 of the striker arms 75. This switch 86 is normally held in active position by the same spring 83 that holds the converter lever in place. It will thus be seen that whenever the boxes are shifted upwardly, one of the branches 88 of the striker arms will engage the switch device 86 and rock the converter lever to depress the latch release 63, and that whenever the boxes are shifted downwardly, the switch 86 will move on its pivot to allow the passage of the striker arms.

Thus whenever a shift of the shuttle boxes takes place in either direction, the mechanism described and illustrated, either through the direct action of the striker arms 85 or through the action of the striker arms transmitted through the converter lever, will depress the latch release 63 swinging the clamping mechanism to open position, releasing the latch arm 49 and permitting the spring 46 to project the clamping mechanism to its rearward position where it will receive within its field of action the filling extending from the selvage to the shuttle which has been shifted to inactive position.

During the normal weaving operation, the filling ends 89 extending to the inactive shuttles are held clamped in the clamping mechanism, as shown in Fig. 1, and hang loosely. There is no particular strain on these fillings and while the clamping mechanism is normally closed, still these filling ends will not withdraw from the clamping mechanism when open because the friction engagement with the fixed clamping members, especially when serrated, as shown in Fig. 6, is sufficient to hold them in place. But when an inactive shuttle is shifted to active position, the clamping mechanism is closed before it starts on its pick, so that the end extending to this shuttle is firmly held when the first pick is laid.

Thus the invention provides means which entirely prevents the formation of the undesirable loops along the selvage of the fabric and which may be embodied in a wide variety of mechanisms suitable for any form of shifting shuttle box loom.

Having thus described the invention, what is claimed as new, and desired to be secured by Letters Patent, is:

1. A shifting shuttle box loom comprising filling clamping mechanism located normally out of position to receive a filling extending from the selvage to an inactive shuttle and means actuated upon each shift of the shuttle boxes to cause the clamping mechanism to move into a position to receive such a filling.

2. A shifting shuttle box loom comprising

- the construction defined in claim 1, together with means actuated by the lay on the beat-up to cause the clamping mechanism to clamp the said filling and to move the clamping mechanism to the said normal location.
3. A shifting shuttle box loom comprising the construction defined in claim 1, together with means actuated by the lay on the beat-up to cause the clamping mechanism to clamp the said filling and to move the clamping mechanism to the said normal location, and means for parting the filling thus clamped between the selvage and the said clamping mechanism.
4. A shifting shuttle box loom comprising a filling clamping mechanism located adjacent, and bodily movable alongside, the selvage on the drop box side, a spring acting normally to project the clamping mechanism rearward of the fell to bring within its field a filling extending from the selvage to a shuttle in inactive position, a latch to hold said clamping mechanism retracted out of position to receive such a filling, means for releasing the latch upon a shifting of the shuttle boxes, and means actuated by the lay on the beat-up to restore the clamping mechanism to retracted position.
5. A shifting shuttle box loom comprising a filling clamping mechanism located adjacent, and bodily movable alongside, the selvage on the drop box side, a spring acting normally to project the clamping mechanism rearward of the fell to bring within its field a filling extending from the selvage to a shuttle in inactive position, a latch to hold said clamping mechanism retracted with the clamping members closed and out of position to receive such a filling, and means for opening the clamping members and releasing the latch upon a shifting of the shuttle boxes to cause the clamping mechanism to be projected forward open.
6. A shifting shuttle box loom comprising the construction defined in claim 5, together with means actuated by the lay on the beat-up to close the clamping members and restore the clamping mechanism to retracted position.
7. A shifting shuttle box loom comprising filling clamping mechanism located adjacent, and bodily movable alongside, the selvage on the drop box side, a spring acting normally to project the clamping mechanism rearward of the fell to bring within its field a filling extending from the selvage to a shuttle in inactive position, a latch to hold said clamping mechanism retracted out of position to receive such a filling, a latch release, an actuator mounted on a stationary part of the loom and movable proportionately with the shifting movement of the boxes, striker members, one less in number than the boxes, carried by the actuator, a switch device on the latch release in the path of the striker members operated, when the actuator moves in one direction, by a striker member to effect a releasing movement of the latch and movable to allow the passage of the striker members when the actuator moves in the other direction, and a converter device in the path of the striker members operated, when the actuator moves in the latter direction, by a striker member to engage the switch device and effect a releasing movement of the latch and acting, when the actuator moves in the former direction, to allow the passage of the striker members.
8. A shifting shuttle box loom comprising filling clamping mechanism located adjacent, and bodily movable alongside, the selvage on the drop box side, a spring acting normally to project the clamping mechanism rearward of the fell to bring within its field a filling extending from the selvage to a shuttle in inactive position, a latch to hold said clamping mechanism retracted out of position to receive such a filling, a latch release, a rod mounted on a fixed part of the loom, connected to the box shifting mechanism and actuated thereby to move proportionately with the shifting movement of the boxes, striker arms, one less in number than the boxes, projecting laterally in parallelism from the rod and spaced apart a distance equal to one unit of movement of the rod, a switch on the latch release in the path of the striker arms operative upon the downward movement of the rod to release the latch and movable to allow the passage of the striker arms upon the upward movement of the rod, a converter lever having one arm extending over said switch, and a second switch on the other arm of the converter lever in the path of the striker arms operative upon the upward movement of the rod to rock the lever to release the latch and movable to allow the passage of the striker arms upon the downward movement of the rod.
9. A shifting shuttle box loom comprising filling clamping and parting mechanism located adjacent the selvage on the drop box side and means to cause said mechanism after a shuttle is shifted from active to inactive position to clamp the filling extending from the selvage to the inactive shuttle and to part the said filling between the selvage and the point at which it is clamped.
10. A shifting shuttle box loom comprising filling clamping mechanism located adjacent the selvage on the drop box side, means to cause said mechanism after a shuttle is shifted from active to inactive position to clamp the filling extending from the selvage thereto and to hold said filling clamped when the said shuttle lays its first pick after being restored to active position and means for parting said filling between

the selvage and the point at which it is clamped.

11. A loom employing a plurality of filling carriers, each of which is independently active in the weaving operation, together with means for throwing any one of the filling carriers out of and another into action and means for restoring the former filling carrier into action without forming a loop of filling from said filling carrier along the selvage.

12. A loom employing a plurality of filling carriers, each of which is independently active in the weaving operation, together with means for throwing any one of said filling carriers out of action and restoring it into action, means for seizing the filling extending to such a filling carrier when out of action and means for parting said filling between the selvage and the point at which it is seized.

13. A shifting shuttle box loom comprising means for seizing adjacent the selvage a filling extending to a shuttle in inactive position, means for then severing the said

filling between the selvage and the point of seizure, the said seizing means holding the said filling after the shuttle returns to active position and while laying its first pick.

14. A shifting shuttle box loom comprising filling clamping mechanism located adjacent, and bodily movable alongside, the selvage on the drop box side, a spring acting normally to project the clamping mechanism rearward of the fell to bring within its field a filling extending from the selvage to a shuttle in inactive position, a latch to hold said clamping mechanism retracted out of position to receive such a filling, a latch release, an actuator mounted on a stationary part of the loom and movable proportionately with the shifting movement of the boxes, and means controlled by the actuator to effect a releasing movement of the latch upon a shift of the boxes in either direction.

In testimony whereof; I have signed my name to this specification.

EDWARD A. CUNNIFF.
